John J. Adams

UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

RADIO SIGNALING.

Application filed August 19, 1921, Serial No. 493,669, and in France August 2, 1917. Renewed August 31, 1928.

(GRANTED UNDER THE PROVISIONS OF THE ACT OF MARCH 3, 1921, 41 STAT. L., 1313.)

This invention particularly relates to improvements in the arrangements described in my U. S. Patent No. 1,405,523, dated February 7, 1922, and to the arrangements described 5 in my copending U. S. applications, Serial No. 243,080, filed July 2, 1918 and Serial No. 493,670, filed August 19, 1921.

In vacuum tube amplifiers such as disclosed in the U. S. patent mentioned, and particularly 10 in reversible amplifiers such as those described in the applications mentioned, it often happens that high frequency oscillations occur notwithstanding the fact that apparatus is provided for amplifying low frequency currents. Due to the presence of this 15 unexpected condition the apparatus will be noisy, will distort when amplifying or will not amplify at all.

In accordance with the present invention 20 this condition is avoided by preventing the existence of an electrical connection between the input and output sides of the apparatus.

This is accomplished by establishing an 25 acoustical connection in the low frequency circuits between the plate circuit of one tube and the grid circuit of the next tube, instead of utilizing the usual electrical coupling through a transformer. By acoustical connection, I refer for example, to the well known 30 connection or coupling which may be established by means of mechanical relays comprising a telephone receiver and a microphone.

Referring to the single-figure drawing, 35 which is a schematic diagram of a preferred embodiment of my invention, a source of radio frequency is connected to the input of the detector, the output of said detector being connected to the input of an audio frequency 40 amplifier. The output of the audio frequency amplifier is connected to a sound reproductive device 1, the sound waves emanating therefrom impinging on a diaphragm of the micro-

phone device 2. The microphone device 2 is connected to the input side of another audio 45 frequency amplifier A₁, whose output side may be connected to a sound reproductive device 3 as shown.

It will be seen that only low frequency oscillations may occur in the audio frequency amplifier A₁, because the diaphragm of the receiver which establishes the connection or coupling vibrates only in response to low frequencies. If the receiver is at a sufficient distance from the transmitter no capacity effect 55 can occur between the input and output of the amplifier, neither can any electro magnetic induction effect take place. Obviously, the acoustical connection may be provided at any point of the circuit. In the case of an 60 amplifying system having a plurality of stages, an acoustical connection may be used for the coupling of two successive tubes.

While I have shown and described a preferred embodiment of my invention I do not 65 limit myself to the same but may employ such other modifications as come within the spirit and scope of my invention.

Having described my invention what I claim is:

1. A multi-stage cascade audio frequency 70 amplifier, each stage comprising a vacuum tube and associated circuits, and a one-way acoustical coupling means between two adjacent stages for electrically isolating portions 75 of said amplifier.

2. An audio amplifier comprising a plurality of stages, each stage including a vacuum tube provided with an input circuit and an output circuit, and a one way acoustical 80 coupling means between the output circuit of one vacuum tube and the input circuit of an adjacent vacuum tube whereby said stages are electrically isolated.

MARIUS LATOUR.
